UNITED STATES PATENT OFFICE.

SIMON COOPER, OF NEW YORK, N. Y., ASSIGNOR TO THE WARREN FEATHERBONE COMPANY, OF THREE OAKS, MICHIGAN, A CORPORATION OF MICHIGAN.

FEATHER-DEBARBING MACHINE.

1,279,275.

Specification of Letters Patent. Patented Sept. 17, 1918.

Application filed September 5, 1916. Serial No. 118,564.

To all whom it may concern:

Be it known that I, SIMON COOPER, a citizen of the United States, and a resident of New York, in the county of New York and 5 State of New York, have invented certain new and useful Improvements in Feather-Debarbing Machines, of which the following is a specification.

My invention relates to a feather debarbing machine, that is, a machine for cutting the barbs from the quills of feathers.

The quill part of feathers is being used extensively for various purposes, as for example in collar supports, wearing apparel stays, 15 etc., and before the quills can be cut up to be used for this purpose the barbs must be removed. Heretofore this has been accomplished by cutting with ordinary knives or 20 knife mechanism, but this procedure has not proven to be very satisfactory. The object of my invention is therefore to produce a machine into which feathers can be rapidly fed and their barbs accurately and speedily 25 cut off. As different feathers have quills of different and varying thicknesses, provision is made in the machine for automatically allowing and adjusting for such variation while the cutting is going on.

A machine embodying the various features of my invention is illustrated on the accompanying drawings in which—

Figure 1 is a front elevational view,

Fig. 2 is a plan view,

Fig. 3 is a sectional view on plane 3—3, 35 Fig. 2, and

Fig. 4 is an enlarged view of the feather propelling and barb cutting heads showing their operation on the feather.

Mounted on the machine foundation 10 are the supporting frames 11 and 12. Mounted on the tops of these frames are journal box supporting structures 13 and 13'. As the construction and arrangement 15 of these structures and the mechanism there- in are identical, I shall describe the mechanism in the structure 13 by ordinary reference numerals and shall apply primed reference numerals to corresponding parts in the structure 13'. At the lower part of the 20 structure 13 is the journal box section 14 in which is journaled a shaft 15 whose axis is inclined with its outer end below the horizontal. At its outer end the shaft carries a conical cutting head 16 and at its inner end

carries the bevel gear 17 and also the transmission gear 18. Above the journal box section 14 is the journal box section 19 in which is journaled a shaft 20 whose axis is inclined with its outer end above the horizontal. The shaft 20 carries at its outer end the conical cutting head 21, and secured to its inner end is the gear 22 which meshes with the gear 18 on shaft 15. The shafts 15' and 20' in the structure 13' have inclined axes with their outer ends respectively below and above the horizontal so that the cutting heads 16' and 21' are opposed to each other but with their axes at angles with each other. The opposed 55 faces of the respective cutting heads being at right angles with the respective axes, these faces will be at angles with each other, the faces of the lower heads being closer together at the top and those of the upper heads being closer together at the bottom. By means of suitable mechanism which will 60 be presently described the lower heads are rotated with their tops moving rearwardly and the upper heads with their bottoms also moving rearwardly. In operating the machine the operator stands in front thereof 65 and inserts feathers one by one into the trough between the upper heads, the feathers being held with their barbs extending laterally and the ends of the feathers are fed into the trough and when they reach the bottom 70 of the trough they will be engaged by the opposed faces of the upper heads and will be propelled rearwardly with the quills between the four opposed edges of the upper 75 and lower cutting heads with the barbs then 80 projecting laterally in the spaces between the upper and lower heads. The outer diameters of the heads are such that the edges 23 and 23' of the lower heads engage against the conical surface of the heads 21 and 21' 85 and the feather barbs being received between the cutting edges and the conical faces will be cut from the quills as they pass through the machine.

Provision is made to cause the engagement between the cutting edges and the conical surfaces to be yielding. I have therefore made the upper journal boxes 19 and 19' vertically movable to the journal boxes 14 and 14'. Referring to the structure 13 an arm 100 24 extends to the right from the journal box 19 and is hinged to the end of the bracket 25 extending to the right from the structure

13. The compression spring 26 is inserted between the top 27 of the structure 13 and the journal box 19, the pressure of this spring being adjustable by means of the set screw 28. In the structure 13' the arrangement is the same, the spring 26' pressing against the journal box 19'. These springs tend to keep the conical faces of the upper cutting heads against the cutting edges of the lower heads, the compression being sufficient to insure cutting through of the barbs as the feathers pass through the machine.

As different feathers have quills of different and varying diameters provision is also made to automatically adjust for such changes. The frame 11 on which the structure 13 is mounted is rigidly secured to the machine base 10, but the frame 12 which supports the structure 13' and the mechanism therein is pivoted to swing about a vertical axis. As shown, the frame 12 extends laterally upwardly from a bearing sleeve 29 which is pivoted on the stud 30 extending upwardly from the machine base. An arm 31 extends forwardly from the sleeve 29 and a tension spring 32 connected between the end of the arm and a post 33 on the machine frame tends to rotate the sleeve and to swing the frame 12 to force the cutting heads 16' and 21' against the heads 16 and 21, an adjustable stop 34 limiting such swing. With this arrangement as the diameters or thickness of quills vary the pivoted arrangement of the frame 12 will permit the opposed cutting heads to move laterally toward or away from each other, the spring 32 being of sufficient strength to hold the heads toward each other with sufficient strength to properly clamp and propel the feathers through the machine during cutting off of the barbs.

Any suitable mechanism may be provided for rotating the cutting heads. As shown, cross shafts 35 and 35' are journaled in the supporting structures 13 and 13' respectively, the shaft 35 carrying a bevel gear 36 meshing with the gear 17 at the front thereof and the shaft 35' supporting a bevel gear 36' meshing with the bevel gear 17 at the rear thereof. At the sides of the machine base 10 standards 37 and 37' are supported and at their upper ends journal the cross shafts 38 and 38' to whose front ends are secured the sprocket wheels 39 and 39' respectively which are in alignment with sprocket wheels 40 and 40' secured to the front ends of the shafts 35 and 35' respectively. At the front of the machine base and at the sides thereof, brackets 41 and 41' support shafts 42 and 42' which carry sprocket wheels 43 and 43' respectively. The shaft 42 is a driving shaft and has secured thereto the drive pulley 44 which is connected by a belt with a suitable driving engine or counter shaft. Around the various sprocket wheels passes a chain 45. As

shown, this chain travels in the direction of the arrows and passes in such direction around the sprocket wheels 40, 40' as to cause clockwise rotation thereof. With the bevel gear arrangement as before described, the lower cutting heads will rotate with their front sides traveling upwardly, and by means of the transmission gears 18, 18', 22 and 22' the upper cutting heads will be rotated with their front faces traveling downwardly (Fig. 1). With such rotation feathers inserted from the front of the machine will be drawn rearwardly.

The cutting heads may be formed integral with their respective supporting shafts, or as indicated in Fig. 3, they may be separate and seated on the reduced end sections 46 of the respective shafts and locked thereto by nuts 48 engaging the threaded ends of the shaft.

The machine I have described is very efficient, feathers fed thereto being rapidly propelled and the barbs cut therefrom and the debarbed quills thrown out. By the adjustable arrangement which enables the cutting heads to yield vertically and laterally the machine operates efficiently on all sizes of feathers, the cutting heads following the various thicknesses of the quills and cutting off the barbs close thereof so that the debarbed quills are ready for the machines in which they are split up into sections or strips.

I do not, of course, desire to be limited to the exact constructions, arrangements and operations described as modifications can no doubt be made which would still come within the scope of the invention.

I claim as follows:

1. In a feather debarbing machine, the combination of opposed bearing structures, upper and lower shafts journaled in each structure, upper and lower pairs of conical rollers secured to the respective ends of the shafts between the bearing structures, the rollers of one pair being separated a greater distance than the rollers of the other pair with the base edges of the one pair cooperating with the conical surfaces of the other pair to cut barbs from feathers passed between the upper and lower pairs during rotation of the rollers, and means for rotating the upper and lower shafts in opposite directions.

2. In a feather debarbing machine, the combination of opposed bearing structures, an upper and a lower shaft journaled in each structure, an upper and a lower pair of conical rollers between the bearing structures secured to the respective ends of the upper and lower shafts, the upper shafts being at angles with each other whereby to provide a guide slot between the outer faces of the opposed upper rollers for feathers, the lower rollers being separated laterally a

distance to bring their base edges opposite the conical surfaces of the upper rollers to coöperate therewith to cut barbs from feathers fed in between the upper rollers, and 5 means for simultaneously rotating said upper and lower shafts in opposite directions.

3. In a feather debarbing machine, the combination of opposed bearing structures, an upper and a lower shaft journaled in 10 each structure, an upper and a lower pair of conical rollers between the bearing structures secured to the respective ends of the upper and lower shafts, the upper shafts being at angles with each other and the lower 15 shafts whereby to form V-shaped guide slots between the opposed rollers for feathers and to provide horizontally extending spaces between the upper and lower rollers for the feather barbs, one pair of rollers being 20 spaced laterally farther apart than the other rollers to bring their base edges opposite the conical surfaces of such other rollers whereby the barbs will be cut from the feathers by such edges during rotation of the rollers, 25 and means for simultaneously rotating the upper and lower shafts.

4. In a feather debarbing machine, the combination of opposed journal boxes, shafts journaled in said journal boxes, rollers secured to the projecting ends of said shafts, one roller having a cutting edge opposed to the surface of the other roller for cutting off barbs of feathers passed between the rollers, and means for yieldingly pressing 30 said journal boxes together to thereby yieldingly press the roller cutting edge and surface together, and means for rotating said shafts.

5. In a feather debarbing machine, the 40 combination of opposed supporting structures, upper and lower journal boxes on each structure, upper and lower shafts in the upper and lower journal boxes of each structure, upper and lower rollers mounted on the projecting ends of the shafts between the 45 structures, said lower rollers having cutting edges for coöperating with the surfaces of the upper rollers to cut barbs from feathers passed between the rollers, means for rotating the upper and lower shafts, and means 50 yieldingly pressing the upper journal boxes toward the lower journal boxes to yieldingly press the journal boxes together.

6. In a feather debarbing machine, the 55 combination of opposed supporting structures, upper and lower journal boxes of each structure, upper and lower shafts in the upper and lower journal boxes of each structure, upper and lower rollers mounted on the 60 projecting ends of the shafts between the structures, said lower rollers having cutting edges for coöperating with the surfaces of the upper rollers to cut barbs from feathers passed between the rollers, means for 65 rotating the upper and lower shafts, and

means whereby one of said supporting structures is laterally yieldable whereby to allow lateral separation of the rollers to accommodate the varying thicknesses of feather stems.

7. In a feather debarbing machine, the combination of opposed supporting structures, upper and lower journal boxes on each structure, upper and lower shafts in the upper and lower journal boxes of each structure, upper and lower rollers mounted on the projecting ends of the shafts between the structures, said lower rollers having cutting edges for coöperating with the surfaces of the upper rollers to cut barbs from feathers 70 passed between the rollers, means for rotating the upper and lower shafts, means yieldingly pressing the upper journal boxes toward the lower journal boxes to yieldingly press the boxes together, one of said supporting structures being pivoted to swing laterally, and yielding means tending to hold the pivoted structure toward the other structure to keep the opposed rollers together but permitting lateral separation of 75 the rollers to compensate for the varying thicknesses of the stems of feathers passing between the rollers.

8. In a feather debarbing machine, the combination of opposed supporting structures, upper and lower journal boxes in each structure, upper and lower shafts in the upper and lower journal boxes of each supporting structure, upper and lower conical rollers between the structures and secured 95 to the projecting ends of the respective shafts, said upper and lower shafts being inclined and with their roller supporting ends farthest away from the horizontal whereby to provide V-shaped guide ways between the 100 opposed rollers for feathers and to provide spaces between the upper and lower rollers for the barbs of feathers, the edges of one set of opposed rollers being offset with reference to the edges of the other rollers to 105 coöperate with the conical surfaces of such other rollers to cut the barbs from feathers, means for simultaneously rotating the upper and lower shafts, yielding means tending to press the upper and lower journal boxes 110 together to yieldingly press the cutting edges and surfaces together, and means for permitting one of said supporting structures to yield laterally whereby to permit yielding lateral separation of the rollers to compensate for the varying thicknesses of the quills 115 of feathers passing through the rollers.

9. In a feather debarbing machine, the combination with means presenting a hard surface, a moving member having a cutting 120 edge continuously coöperating with said surface to cut barbs from feathers passed between said edge and surface, and means for automatically causing said cutting edge to move in conformity with the contour of the 125

quills of the feathers during debarbing thereof.

10. In a feather debarbing machine, opposed rotary members, one of said members presenting a backing surface and the other member having a cutting edge in a plane at a considerable angle with said surface for cooperating with said surface to propel feathers and to sever the barbs therefrom during such propulsion.

11. In a feather debarbing machine, the combination of a rotary member having a peripheral backing surface for barbs of feathers, a rotary cutter member having a cutting edge presented to said surface, and means for rotating said members at uniform peripheral speed whereby the engagement of said barbs between said surface and cutting edge will cause propulsion of the feathers and cutting of the barbs therefrom.

12. In a feather debarbing machine, the combination of rollers, one of which has a cutting edge presented to a surface of the other at a considerable angle to sever by

pressure the barbs of feathers passed between the rollers.

13. In a feather debarbing machine, the combination of two conical rollers, the base plane of one roller being offset axially with reference to the base plane of the other roller whereby the base edge of the one roller will engage with the conical surface of the other roller, and means for rotating said rollers to cause severing by pressure of the barbs of feathers fed between said conical surface and edge.

14. In a feather de-barbing machine, means comprising a surface and a cutter disk having a peripheral cutting edge and positioned for rolling and pressure engagement with said surface to propel feathers between said surface and edge and to cut barbs therefrom.

In witness whereof I hereunto subscribe my name this 18th day of August, A. D. 45 1916.

SIMON COOPER.
